UNITED STATES PATENT OFFICE.

CHARLES E. MCBETH, FREDERICK BENTEL, AND WILLIAM C. MARGEDANT, OF HAMILTON, OHIO, AND HENRY CLIMER, OF MUSCATINE, IOWA.

IMPROVEMENT IN PLANING-MACHINES.

Specification forming part of Letters Patent No. 120,448, dated October 31, 1871.

To all whom it may concern:

Be it known that we, CHARLES E. MCBETH, FREDERICK BENTEL, and WILLIAM C. MARGEDANT, of Hamilton, in the county of Butler and State of Ohio, and HENRY CLIMER, of Muscatine, in the county of Muscatine and State of Iowa, have invented a new and Improved Universal Wood-Working Machine; and we do hereby declare that the following is a full, clear, and exact description thereof, which will enable others skilled in the art to make and use the same, reference being had to the accompanying drawing forming part of this specification.

Figure 1 represents a front elevation of our improved wood-working machine. Fig. 2 is a plan or top view of the same. Fig. 3 is a detail vertical transverse section of the adjustable fence used on the machine. Fig. 4 is a detail longitudinal vertical section of the adjustable front table. Fig. 5 is an end view of the machine. Fig. 5^a is an inner end view of one of the front tables. Fig. 6 is a front view, partly in section, of the saw-board attachment. Fig. 7 is a plan or top view of the same. Fig. 8 is a plan or top view of the adjustable gaining-frame. Fig. 9 is an end view of the same. Fig. 10 is a face view of the feed-roller and gearing. Fig. 11 is a vertical section of the same on the line c c, Fig. 10.

Similar letters of reference indicate corresponding parts.

This invention relates to improvements in the universal wood-working machine for which Letters Patent of the United States, dated November 27, 1866, and numbered 59,966, were granted to Henry Climer and John D. Riley. The present invention consists chiefly in a new arrangement of adjustable tables, whereby certain advantages are secured in wood-working, as hereinafter described.

A in the drawing represents the supporting-frame of the machine, made of cast-iron, wood, or other suitable material, of such proper size, form, and strength as to sustain the several appendages, shafts, &c., which constitute the working mechanism. B is the driving-shaft of the machine. It is horizontally hung in the frame A, and receives rotary motion by suitable means, transmitting it by gear-wheels a a b b to the feed-rollers on the molding attachment or sticker, and by belt or otherwise to the mandrel C hung transversely in the upper part of the machine. D is

the vertically-adjustable back-table of the machine. It rests upon wedge-shaped projections d d of a longitudinally-movable carriage, E, that can be moved by means of a screw, e. The table D has no horizontal motion whatever, neither laterally nor lengthwise, but is only vertically adjustable in the manner stated. In front of the back table D are the adjustable front tables F and F'. These consist of the table-tops f f' and table-frames g g', and are connected with them by bolts and nuts h. A spring-pawl, i, projects from each table-frame into a toothed portion, j, on the under side of each table-top, and arrests the latter in any position, preventing it from sliding toward the cutter, permitting, however, when drawn out of the rack, longitudinal adjustment of the top on the frame. Each table-frame g g' rests upon wedge-shaped projections K K of a longitudinally-adjustable carriage, G, which can be set by means of a screw, l. By moving the carriage lengthwise the tables with their frames are adjusted vertically. From the inner end of each table-frame g g' projects an inclined rod, m, into and through a tube, n, pivoted to the frame A. Whenever the screws l are turned to elevate the tables F F' the angle-irons m, sliding in the swinging tubes n, will cause an advancing movement of the tables toward the rotary on the mandrel C. It will be seen that the mandrel, carrying a suitable cutter, H, is hung in the frame A so as to be about midway between the tables F F'. These tables can be set at the same height to serve as an ordinary planing-table, or at different heights for planing out of wind, pointing, or squaring. For planing out of wind the front table or bed behind the knives should be adjusted to the height of the circle described by the knives when revolving. The other bed or front table in front of the knives is then lowered according to the thickness of cut desired. These adjustments can be made in a moment, while the machine is in motion. The stuff is passed over the knives, and after having reached the bed behind the knives has a solid bearing, and will consequently be placed perfectly out of wind and smooth. A fence, I, is placed upon the back table D, and serves as a guide for the stuff to rest against at a suitable angle while passing over the knives. After the stuff has been placed out of wind on one side it can be jointed or squared by turning the planed side next to

the fence and passing over the knives as before. For tapering, the front table in front of the cutter should be lowered according to the taper required, the stuff resting on both front tables before commencing to plane. The fence I is, by pivoted arms o o, connected with slides J J fitted upon the back table D, said slides being slotted to be laterally adjustable on the back table. Slotted rods p p, projecting from the back of the fence and resting in horizontal grooves of the slides J, serve as braces for holding the fence in any suitable inclined position, and are locked by thumb-nuts r to secure the fence vertically or inclined. The stuff is leaned against the inclined fence whenever beveling is to be done. In Figs. 8 and 9 is shown the adjustable gainer-frame L, and by dotted lines in Fig. 2 its application to the front tables. It consists of a sliding-board, s, placed in the recess of the front table-top, and has pivoted to it a guide-rest, t, that carries a sliding end-rest, u. The guide-rest has a slotted arc, v, which is, by a screw, w, clamped to the board s in any suitable position to set the guide-rest obliquely, as required. In arranging for gaining, a proper gaining-head is placed on the mandrel, and the back table D lowered or raised to leave as much head above it as depth of gain required. The gaining-frame, which is quickly adjustable for any angle, is with the slide-board placed into the recesses of one front table, the guide-rest t lying level on front and back tables, as indicated in Fig. 2, the front tables having been adjusted as to height accordingly. The stuff is placed in front of the guide-rest and then moved along with the gaining-frame. Gains can be made straight at an angle part way through, and of any desired shape and size. For plowing, the fence is used as a guide, and two or three heads can be used at the same time, which will work equally well for gaining or plowing. M is the adjustable saw-board. It is, when used, placed upon the ends of the front frames g g' and under the noses of the front table-tops f f', as is clearly shown in Figs. 6 and 7. It requires no other fastening. A saw, N, mounted upon the mandrel C, projects through a slot of the saw-board M, two or more saws being used, if desired. The board M, it will be seen, is flush with the front tables F F', so that thus a superior bed for sawing is obtained. The fence I may be used when ripping, and removed for cross-cutting, in which latter case the bed D is brought flush with the tables F F'. O represents a sticker or additional table affixed to the back of the frame A to constitute a molding attachment. The mandrel C

is elongated to extend partly over the table O, as shown, and carries a head, P, above the same for planing, if desired, on two or more sides at once. R R are the feed-rollers for this molding attachment. They are hung in a removable cap, S, which is by a pin, X, fastened to the frame A, and carry pinions y y, gearing by the wheels b a, into the driving-shaft B, as is clearly shown in Figs. 10 and 11. The bed O can be made vertically adjustable under the feed-rollers R for planing or molding thicker or thinner stuff. The molding-head T is mounted upon a shaft, U, which is hung to a downward extension of the sticker, and can be adjusted laterally and swung to a suitable angle. V represents the rabbeting-iron. It is provided with projecting pins z z, which enter apertures in the ends of the table-tops f f', and is also held in place by the noses of these tops, as shown in Figs. 1 and 2. It serves thus to bridge both front tables, and gives room for the rotary cutter. The rabbeting-cutter, shown also in Figs. 1 and 2, has spur-knives a' a' near its end, which pass close to the rabbeting-iron, so as not to tear or splinter the material when tenoning and rabbeting.

Having thus described our invention, we claim as new and desire to secure by Letters Patent—

1. The arrangement of the spring-pawls with racks i j, table-tops f f', and frames g g', as specified.

2. The front table-tops f f' placed upon the front frames g g', and locked thereto by the spring-pawls and racks i j, as set forth.

3. The longitudinally-adjustable carriages G, carrying the inclines K K, and combined with the front tables F F', rods m, and pivoted tubes n, all arranged to operate substantially as herein shown and described.

4. The gainer-frame L, provided with the guide-rest t and end-rest u, substantially as herein shown and described.

5. The adjustable saw-board M, slotted as described, and combined with the front frames g g' and table-tops f f', in the manner specified.
